(57) **CLAIM**

The ornamental design for shorts with fly flap, as shown and described.

DESCRIPTION

FIG. 1 is a front perspective view showing the ornamental design of the claimed shorts with fly flap;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a perspective view with the flap in a lowered position.

In all of the figures, the dash-dash broken lines are for the purpose of illustrating portions of the shorts with fly flap that form no part of the claimed design.
